UTILITY CHEST

Louis M. Piker, Hamilton, Ohio, assignor to The
Hamilton Metal Products Company, Hamilton,
Ohio, a corporation of Ohio

Application June 25, 1937, Serial No. 150,346

7 Claims. (Cl. 206—16)

This invention relates to improvements in chests or boxes, such as is used for carrying about tools, fishing tackle, makeup and similar materials.

5 One of the objects of this invention is to provide a box of this type, having hingedly connected to the lid thereof a tray, and in which the tray and lid co-operate with one another to limit the opening of the lid and retain same in an 10 open position.

Another object of this invention is to provide a utility box or chest of the type above indicated, in which the lid, when open, holds the tray therein in a horizontal position, and in which 15 the lid is retained in a substantially upright position.

A further object of this invention is to so construct the parts as to result in a box in which the parts are freely movable relative to one another, 20 while accomplishing the above objects.

Other objects and advantages of the present invention should be readily apparent by reference to the following specification, considered in conjunction with the accompanying drawing 25 forming a part thereof, and it is to be understood that any modifications may be made in the exact structural details there shown and described, within the scope of the appended claims, without departing from or exceeding the spirit of the 30 invention.

In the drawing:

Fig. 1 is a perspective view of a utility chest or box embodying the improvements of this invention.

35 Fig. 2 is a fragmentary, sectional view taken on line 2—2 of Fig. 1.

Fig. 3 is a fragmentary, sectional view, taken on line 3—3 of Fig. 2.

Fig. 4 is a fragmentary, sectional view, through 40 the pivot connection of the arm with the tray, taken on line 4—4 of Fig. 3.

Fig. 5 is an end, elevational view of the utility chest of Fig. 1, showing the lid closed, and with the tray in dotted position within the chest.

45 Fig. 6 is a perspective view of the hinge pin and bumper utilized in this construction, and forming a detail of the invention.

Fig. 7 is a perspective view of a portion of Fig. 1, which illustrates a modification of the invention; and,

50 Fig. 8 is a fragmentary, sectional view taken on line 8—8 of Fig. 7.

Throughout the several views of the drawing, similar reference characters are employed to denote the same or similar parts.

The utility chest or box of this invention comprises a box-like member 10, having a bottom 11, front 12, back 13 and ends 14 and 15. The front, back and ends are suitably ribbed and embossed for strength and ornamentation, as is frequently done to articles of this nature, and in which the upper rib or bead 16 is utilized as a lip for the edge of the lid or cover 17. The portion 18, of the front, back and ends above the bead or rib 16 therein, are inwardly offset with respect to 10 the rest of these parts.

The lid or cover 17, comprises a body or top portion 19, from which depends a front flange 20, a rear flange 21 and end flanges 22 and 23. These flanges are adapted to be in the plane of 15 the box front, back and sides, below the bead or rib 16, when the said cover 17 is closed, and are adapted to overlie the portion 18, as above described. The lower edge of the back flange 21 is turned to form an eye for a hinge pin 34, which 20 hinge pin has its ends disposed in a reversely formed bead 35 in the back 13 of the box. This bead 35 is in line with the bead 16 and is, in fact, a continuation of this bead. From this, it will now be seen that the cover 17 is hingedly 25 connected with the box 10, for movement relative thereto.

Disposed longitudinally of the box 10 and cover 17, and interiorly thereof, is a tray 24, of a width somewhat less than the width of the box, so as 30 to provide the space 25 between said tray and the front 12 of the box, when the cover is open, whereby access may be had to the interior of the box. This tray 24, comprises a bottom 26, a front 27, back 28 and ends 29 and 30. The upper 35 ends of the tray front, back and ends are rolled to provide a bead 31, and which bead, on the tray front 27 and ends 29 and 30, overlies the upper edge of the box front 12, and ends 14 and 15, while remaining within the confines of the lid or 40 cover flanges. The opposite ends of the bead of the tray back 28 are utilized for securing therein pivot or hinge pins 34 and 32, which project beyond the ends of the tray, through suitable apertures 33 formed in the cover end flanges 22 and 45 23. Movement of the cover 17, about the axis of the hinge pin 34, will carry with it the rear end of the tray 24. In order to maintain the tray in a horizontal position at all times during the movement thereof, it has its forward end connected to a pair of arms 36 and 37 of which arm 37 is most clearly shown in Fig. 4.

As is shown, the arm 37 comprises a body portion 38, having its upper end bent normal thereto, as at 39, to enter a socket 40, formed in the 50 55

bottom 26 of the tray, near the front wall or flange 27 thereof. The lower end of the body portion 38 of the arm 37 is likewise bent normal thereto, as at 41, which passes through an aperture 42 in the box body side. The free end of the arm portion 41 is peaned over to form a head 43, which prevents the pin from being inwardly withdrawn from the aperture 42. From the foregoing, it will now be appreciated that movement 10 of said cover 17 carries with it the tray 24, which is at all times maintained in a horizontal position during the movement of said cover.

In order to limit the opening of the cover 17, there is provided, in connection with the tray 24, 15 a bumper, which engages the inner or under surface of the cover top 19. This bumper, as shown in Figs. 2, 3 and 6, is formed integral with the hinge pins 31 and 32, and one of which hinge pins, 31 for example, is illustrated in detail in Fig. 6 and to which reference is now to be had.

This combined hinge pin and bumper, comprises a straight portion 44, which forms the pin 31, and from which a portion 45 projects in a downwardly and outwardly, angular direction.

25 At the end of the portion 45, the pin is bent at right angles to provide the portion 46. The material forming the connection or bend at 47 between the pin portions 45 and 46 constitute the contact bumper portion, and engages the inner surface of the cover top 19, as illustrated clearly in Fig. 2. It should be noted at this time that the pin portion 47 could be cut off and the end of the pin portion 45 left thereby, and positioned at 47 could be utilized as the contact bumper. 30 With this construction, the movement of the lid or cover 27 in an opening direction could be limited by positioning the lid vertically with respect to the box, or positioning said lid at a point slightly ahead of or behind the vertical position, and with the tray 24 at all times in a horizontal position.

With this construction, the tray is positioned to have its weight, plus the weight of the content thereof, forwardly of the hinge pin 34, thereby 45 preventing a rearward tilting of the box 10, when the cover 17 is open, since the center of gravity will then be forwardly of the hinge pin 34.

In Figs. 7 and 8, a slight modification is illustrated in a bumper construction, which will accomplish the same result as the structure above described. In this construction, one or more tongues or tabs 48 are struck from the rear wall or flange of the tray, which are adapted to have their inner ends 49 engage the inner surface of the cover or lid, and accomplish the positioning of the said cover or lid in the same manner as the contact bumper above described accomplished that result.

From the foregoing, it will now be appreciated that there has been provided a chest or box, having hingedly connected thereto a tray, which cooperates with the cover or lid of the chest for positioning the cover and, at the same time, maintain the parts in such a position that the box 60 is not tilted when the cover is open.

What is claimed is:

1. In a chest of the class described, the combination of a box having a cover hingedly connected thereto, a tray pivotally connected to said cover, and means associated with and projecting rearwardly from said tray for engaging the cover portion of the cover to limit the opening of said cover, to position same with respect to the box comprising a bumper projecting rearwardly from the tray.

2. In a chest of the class described, the combination of a box having a cover hingedly connected thereto, a tray pivotally connected to said cover, means associated with and projecting rearwardly from said tray for engaging the cover portion of the cover to limit the opening of said cover, to position same with respect to the box comprising a bumper projecting rearwardly from the tray, and means for maintaining the tray in a horizontal position during the movement thereof with the cover.

3. In a chest of the class described, the combination of a box having a cover hingedly connected thereto, a tray pivotally connected to said cover, means associated with and projecting rearwardly from said tray for engaging the cover portion of the cover to limit the opening of said cover, to position same with respect to the box comprising a bumper projecting rearwardly from the tray, and means for maintaining the tray in a horizontal position during the movement thereof with the cover, comprising an arm having one end pivotally connected to the box, and the other end pivotally connected with the tray.

4. In a chest of the class described, the combination with a box, of a cover having depending flanges pivotally connected to the box, a tray within the cover and having hinge pins projecting from the ends thereof through apertures in the cover flange whereby movement of the cover from a closed to an open position carries with it the tray, means connecting the tray with the box for maintaining the tray in a horizontal position during the movement thereof, and means associated with said tray for engaging the box cover 30 to limit its movement in an opening direction and thereby position said box cover relative to the box, comprising a bumper projecting rearwardly from the tray.

5. In a chest of the class described, the combination with a box, of a cover having depending flanges pivotally connected to the box, a tray within the cover and having hinge pins projecting from the ends thereof through apertures in the cover flange whereby movement of the cover from a closed to an open position carries with it the tray, means connecting the tray with the box for maintaining the tray in a horizontal position during the movement thereof, and means associated with said tray for engaging the box cover 35 to limit its movement in an opening direction and thereby position said box cover relative to the box, comprising a bumper integral with the tray hinge pins and so arranged to engage the cover and limit its movement in an opening direction 40 and substantially vertically position the cover with respect to the box.

6. In a chest of the class described, the combination with a box, of a cover having depending flanges pivotally connected to the box, a tray within 45 the cover and having hinge pins projecting from the ends thereof through apertures in the cover flange whereby movement of the cover, from a closed to an open position, carries with it the tray, means connecting the tray with the box for 50 maintaining the tray in a horizontal position during the movement thereof, and means associated with said tray for engaging the box cover to limit its movement in an opening direction 55 and thereby position said box cover relative to the box, comprising lugs struck from, and projecting rearwardly of, the tray for engaging the cover.

7. In a chest of the class described, the combination with a box, of a cover having depending 55

flanges pivotally connected to the box, a tray within the cover and having hinge pins projecting from the ends thereof through apertures in the cover flanges, whereby movement of the cover from a closed to an open position carries with it the tray, an arm having trunnions at opposite ends thereof, a socket in the bottom of the tray receiving one of the arm trunnions, an aperture in the box receiving the other arm trunnion, said arm and

its connection providing means for maintaining the tray in a horizontal position during the movement of the cover, and means associated with said tray for engaging the cover portion of the box lid to limit the movement in an open direction and thereby position said box cover relative to the box comprising a bumper projecting rearwardly from the tray. 5
